ATTORNEYS

UNITED STATES PATENT OFFICE.

AUGUST CHARLES KLOPPER, OF ASBURY PARK, NEW JERSEY.

WRENCH.

1,385,214.

Specification of Letters Patent.

Patented July 19, 1921.

Application filed November 6, 1920. Serial No. 422,225.

To all whom it may concern:

Be it known that I, AUGUST C. KLOPPER, a citizen of the United States, and a resident of Asbury Park, in the county of Monmouth and State of New Jersey, have invented a new and Improved Wrench, of which the following is a full, clear, and exact description.

This invention relates to improvements in wrenches, an object of the invention being to provide a gear drive socket wrench which can be conveniently used for removing or replacing nuts which are awkward to reach and operate with wrenches such as ordinarily made.

A further object is to provide a socket wrench of the character stated, which can be operated to lock the socket against turning movement to permit the full leverage of the wrench to be employed for loosening a nut and then enable the socket to be turned by the gear driven mechanism to complete the removal of the nut.

A further object is to provide a wrench of the character stated which can be manufactured and sold at a reasonably low price and which will most efficiently perform the functions for which it is intended.

With these and other objects in view the invention consists in certain novel features of construction, and combinations and arrangements of parts, as will be more fully hereinafter described and pointed out in the claims.

In the accompanying drawings—

Figure 1 is a sectional plan view illustrating my improved wrench.

Fig. 2 is a fragmentary view in elevation or top plan of Fig. 1.

Fig. 3 is a view in section on the staggered line 3—3 of Fig. 1.

Fig. 4 is a view similar to Fig. 3, showing the parts differently positioned.

1 represents a tubular arm or casing having angles or L's 2 and 2' secured on its respective ends and oppositely positioned as clearly shown in Fig. 1. In the angle 2' a bearing sleeve 3 is rigidly secured and provides rotary mounting for a drive shaft 4 having an operating handle 5 fixed to its outer end.

A shaft 6 is located in the tubular casing or arm 1 and is provided with enlarged journals 7 adjacent its respective ends which turn freely in the casing. Beveled pinions 8 and 9 are fixed or made integral with

the respective ends of the shaft 6 and the pinion 8 meshes with a beveled pinion 10 on the inner end of the drive shaft 4, the latter having an annular enlargement 11 60 thereon bearing against the inner end of the sleeve 3, as clearly shown in Fig. 1.

The angle 2 is provided with a tapering ring 12 in which a short shaft 13 is mounted to turn and is provided with a beveled gear 14 meshing with the beveled pinion 9 and driven by the latter. This shaft 13 is made angular at its outer portion as shown at 15, and a socket 16 is secured on this angle member 15. This socket 16 is of such size 70 and shape as to engage a nut and can be made interchangeable with other sizes of socket for various sizes of nut, as will be readily understood.

The gear 14 is provided with an angular 75 recess 17 which is of the same cross-sectional shape as an angular locking block 18, the latter moving in an opening or bearing 19 in the angle 2, and having its end normally spaced from the gear 14 so as to permit the 80 latter a free turning movement. An operating rod 20 projects laterally through the angle 2 and has an operating button 21 on its outer end. This rod 20 is connected by a link 22 with the locking block 18, said 85 link being normally disposed at an angle, as shown in Fig. 3, so that when the rod 20 is drawn outwardly, a longitudinal movement will be imparted to the locking block 18 to force the same into the recess 17 of 90 pinion or gear 14 and lock the pinion against turning movement.

The operation is as follows: The socket 16 is located over the nut and if greater power is required and is possible through 95 the medium of the gearing, the locking block 18 is operated by the rod 20 to lock the pinion 14 against turning movement as the locking block will serve as a coupling device, coupling the pinion and the angle 2 100 together. When the pinion is thus locked, the full leverage of the wrench can be employed to unlock or release the nut, when the rod 20 can be forced inwardly to disengage the locking block 18 from the pinion 105 14 and the gearing and power transmission can be operated through the medium of turning the handle 5, as will be readily understood, to quickly turn the nut.

By reason of the construction above described, it can be seen that my improved wrench can be used in awkward places dif-

ficult to reach by the ordinary wrench, and the gearing can be employed as a socket turning means, or the wrench as a whole can be utilized as a lever, as occasion may 5 require.

Various slight changes might be made in the general form and arrangement of the parts described without departing from the invention, and hence I do not limit myself 10 to the precise details set forth, but consider myself at liberty to make such changes and alterations as fairly fall within the spirit and scope of the appended claims.

I claim:

15 1. A wrench of the character described, comprising a tubular casing, a shaft supported by the casing at one end thereof, a nut engaging socket on the shaft, a pinion on the inner end of said shaft having an 20 angular socket therein, an angular locking block movable into and out of engagement

with said socket and adapted when in engagement with the socket to lock the pinion against turning movement, means for operating the locking block, and means for 25 imparting turning movement to the pinion.

2. A wrench of the character described, comprising a support, a shaft projecting into the support, a socket on the outer end of the shaft, a pinion on the inner end of 30 the shaft having an angular recess therein, an angular locking block keyed to the support and movable into and out of the recess of the pinion, a rod projecting through the support, a link connecting the rod whereby 35 the movement of the rod imparts longitudinal movement to the locking block, and power transmission gearing operatively engaging said pinion.

AUGUST CHARLES KLOPPER.

Witness:

HARRY J. BODINE.
